UNITED STATES PATENT OFFICE.

JOSEPH CHALOUPKA, OF OMAHA, NEBRASKA.

HOSE CLAMP.

1,413,003.

Specification of Letters Patent. Patented Apr. 18, 1922.

Application filed February 21, 1922. Serial No. 538,340.

To all whom it may concern:

Be it known that I, JOSEPH CHALOUPKA, a citizen of the United States, residing at Omaha, in the county of Douglas and State 5 of Nebraska, have invented certain new and useful Improvements in Hose Clamps, of which the following is a specification.

This invention has for its object, broadly, to provide a clamp for a lawn or garden 10 hose which will be convenient, effective and durable in use, and will consist of few and simple parts so that it may be economically manufactured.

The invention consists of the novel construction, combination and arrangement of parts as described herein and claimed, and as illustrated in the accompanying drawing, 15 wherein,—

Fig. 1 is a plan view of a metallic band 20 or strap employed. Fig. 2 is a side view of the hose clamp. Fig. 3 is a view in transverse section through a hose and its coupling-sleeve, showing the device applied thereto, the band and saddle being in longitudinal section. Fig. 4 is a plan view 25 of the hose clamp, the screw being shown in section. Fig. 5 is a plan view of a coupling-nut. Fig. 6 shows a modified form for the band.

Referring now to the drawing for a more 30 particular description, I provide a saddle 6 having a curvature conforming, approximately, to the convexed surface of a hose-pipe 7, the saddle being provided with a pair 35 of opposed wings 8, said wings being provided at their middle, above the saddle, with a bridge or apertured bearing-plate 9. The wings are also connected, near their ends, 40 with pintles or pivot pins 10 on which are mounted rollers 11.

Numeral 12 indicates a coupling-nut having 45 a pair of projections 13 at its opposed sides, and also provided with guides 14 arranged in pairs adjacent to and at the sides 50 of said projections.

Numeral 15 indicates a screw provided with a hand-piece 16, said screw being threaded in the nut 12 and revolvably mounted in the aperture of the bearing-plate 9.

I provide a band or strap preferably 55 consisting of a main body portion 17 having a slot 18 formed therein and having comparatively narrow end-portions 19 provided with apertures 20.

In operation, the saddle is placed on the

hose, the nut 12 being rotated until it is disposed near the bearing-plate or bridge 9. The strap is then placed to completely encircle the hose, one of its end-portions 19, for this purpose, engaging in the slot 18, 60 the end-portions 19 of the strap engaging between the guides 14, and the apertures 20 receiving the projections 13 of the coupling-nut 12. The screw is then rotated in a direction to cause the coupling-nut to 65 move outwardly from the saddle, with the result that the strap will be pressed against the hose for pressing said hose against a sleeve-coupling 21, the rollers 11 operating to maintain the end-portions of the strap, 70 for a part of their length, in engagement with the convexed surface of the hose.

Among some of the advantages to be derived by use of the invention, it is considered that the parts for causing pressure 75 of the band upon the hose may be conveniently operated, and that the degree of pressure, on account of the arrangement of parts as described, will be greater than ordinary. It will be noted that the band 17 is adapted 80 to encircle the hose twice, or nearly so. When the screw is rotated, the nut, together with the ends of the band will move outwardly from the saddle, the force provided by the screw being very effective, the width 85 of the end-portions 19 of the band corresponding approximately, to the width of the slot 18, so that there will not be any appreciable friction, the rollers 11 also tending to prevent friction while operating to 90 maintain the end-portions, or parts thereof, in engagement with the hose.

I claim as my invention:

1. In a hose clamp, a saddle provided with wings and adapted to engage the hose, a bridge outwardly of the saddle carried by the wings, rollers outwardly of the saddle carried by the wings, a screw revolvably mounted in the bridge, a nut having projections and engaging the screw, and a band 100 adapted to encircle the hose and having end-portions adapted to engage the rollers and the projections of the nut, said screw being revolvable for moving the nut outwardly from the saddle.

2. In a hose clamp, a curved saddle provided with wings and adapted to engage the hose, a bridge outwardly of the saddle midway between the ends of and mounted in the wings, pivot-pins at opposed sides of 110

the bridge and mounted in said wings, a screw revolvably mounted in the bridge, a nut on the screw and provided with fastening devices, rollers on the pivot-pins, a band adapted to encircle the hose and having end-portions provided with fastening devices for engaging the fastening devices of the nut, said screw being revolvble for moving the nut outwardly from the saddle, the end-portions of the band engaging said rollers.

3. In a hose clamp, a saddle provided with wings, rollers outwardly of the saddle carried by the wings, a pivotally mounted screw supported outwardly of the saddle by said wings, a nut on the screw having a pair of projections and a pair of guides at the sides of each projection, and a band adapted to engage the hose, said band having end-portions adapted to engage the rollers and the 20 projections between the guides of the nut,

said screw being revolvble for moving the nut outwardly from the saddle.

4. In a hose clamp, a saddle provided with wings, a bridge outwardly of the saddle mounted in said wings, a screw journaled 25 in the bridge, a nut on the screw and having a pair of projections, a band adapted to engage the hose and having end-portions adapted to engage the projections of the nut, said screw being movable for moving 30 the nut and parts of the band outwardly from the saddle, and means carried by said wings adapted to engage parts of the band moved by the movement of the screw.

In testimony whereof, I have affixed my 35 signature in presence of two witnesses.

JOSEPH CHALOUPKA.
